(57) **CLAIM**

The ornamental design for a printer with copying and facsimile functions, as shown and described.

DESCRIPTION

FIG. 1 is a perspective view of a printer with copying and facsimile functions;

FIG. 2 is a front view thereof;

FIG. 3 is a rear view thereof;

FIG. 4 is a right side view thereof;

FIG. 5 is a left side view thereof;

FIG. 6 is a bottom view thereof;

FIG. 7 is another perspective view showing the top of the printer rotated 45°, and,

FIG. 8 is another perspective view showing the top of the printer rotated 180°.

The broken line showing defines the bounds of the claimed design but does not form part of the claimed design.

1 Claim, 6 Drawing Sheets

FIG. 1

FIG. 2**FIG. 3**

FIG. 4**FIG. 5**

FIG. 6

FIG. 7

FIG. 8
